UNITED STATES PATENT OFFICE.

JOHN C. LINCOLN, OF CLEVELAND, OHIO, ASSIGNOR TO THE LINCOLN COMPANY, OF CLEVELAND, OHIO, A CORPORATION OF OHIO.

ELECTRIC-ARC LAMP.

1,031,352.

Specification of Letters Patent.

Patented July 2, 1912.

Application filed March 15, 1905. Serial No. 250,217.

To all whom it may concern:

Be it known that I, JOHN C. LINCOLN, a citizen of the United States of America, and a resident of Cleveland, in the county of 5 Cuyahoga and state of Ohio, have invented certain new and useful Improvements in Electric-Arc Lamps, of which the following is a specification.

My invention relates to improvements in 10 electric arc lamps, and has for its object, the provision of a structure of extreme simplicity; combined with high efficiency and durability in operating the lamp. In structures of this character, the reduction of the several 15 parts to a minimum, is not only desirable on account of reducing the chances for the lamps to get out of order, but because of the greater economy secured in building such lamps. Efforts directed along similar 20 lines have not infrequently resulted, however, in the production of a more or less complex or impractical lamp structure, and, accordingly, I have devised one providing direct and immediate adjustment of the upper 25 and movable carbon, in connection with positive means for producing a substantially constant field for regulating such adjustment. Briefly referring to such means, I may state that they comprise a structure, 30 wherein the traveling armature which carries the upper carbon, is equipped with contacts adapted automatically to maintain in circuit a predetermined number of turns or windings of the field coils, whereby a substantially 35 constant pull or lifting effect is secured. Thus, in the structure which I shall presently describe, the field-coil is seen to comprise windings with which the traveling armature is adapted to make contact, thus 40 including a definite number of turns or windings thereof in any of its positions of adjustment whereby current is supplied thereto, and which exerts the requisite and substantially 45 constant lifting effect.

Specific reference to this structure, as depicted in the accompanying drawings, will make my invention much more readily understood, in which drawings;—

Figure I., is a view in elevation of a lamp 50 designed for use upon constant potential circuits, and including or employing my invention; the said figure being partially broken away in order to illustrate the interior construction. Fig. II., is a vertical sectional view of the said lamp. Fig. III., is

a transverse section of a lamp of somewhat modified construction, and is adapted for use upon constant current circuits. Fig. IV., is a transverse section on line IV.—IV., through the arc-lamp and the armature thereof. 60 Fig. V., shows the blank for forming a modified type of armature. Fig. VI., is an enlarged detail showing the construction of the field windings, whereby the magnetic flux is facilitated; Fig. VII., is an enlarged 65 detail illustrating the segmental form of armature. Fig. VIII., is an enlarged fragmentary view in cross-section, illustrating the details of the field construction with the windings contacting interiorly and exteriorly with the adjacent flanged rings. Fig. IX., is a diagram illustrating the electrical relation of the members of my improved arc lamp; and Fig. X., is a plan view showing the improved damping device. 75

Throughout each of the several figures of the drawings, I have employed the same character of reference to indicate similar parts, in order to obviate any confusion.

The outer casing *a* of the lamp, serves as 80 a return magnetic circuit for the field-windings, being formed of an iron tube or shell adapting it for this purpose. Positioned within the casing, are the two conducting rods *b*, *c*, which respectively carry current 85 to the armature, field-windings, and upper carbon, and from the lower carbon to the external circuit. The rod *c* is serrated, and co-operates with the checking or damping device, in a manner which I shall later 90 explain. Within the casing *a*, but insulated therefrom, and from each other, are the field-coils or windings *d*, a given section or portion of which is excited to provide the magnetic field for supporting the armature 95 *e*, and the upper carbon *f* of the lamp. This coil is formed of flat copper wire, of which the turns are respectively insulated from each other, while affording an annular surface for contact with the co-acting rings carried upon the armature. The said armature is provided with an upper contact ring *e'* connecting with the contact rod *c*, and circumferentially with the field-windings *d*, 105 while a lower contact ring *e''* is electrically connected with the tubular iron armature, and, through the medium of the same, with the upper carbon-holder *f'*. This structure accordingly, insures a constant number of 110 excited turns in the field-windings during

the operation of the lamp, whatever the position of the armature may be, since those turns alone are in circuit which chance to be between the upper and lower contact rings 5 upon the armature.

It will be observed that the tubular iron armature is annularly recessed or cut away, for the purpose of increasing the air-gap midway thereof, and preventing, as far as 10 possible, the short-circuiting or closure of the lines of force within the area of the excited portion of the field-windings.

Pivottally mounted upon a fiber block *g*, is the weighted lever *h* and its detent *h'*, which engage the serrations or teeth provided upon the rod *c*. This construction, it will be seen, serves as a check to prevent the sudden movement of the armature, and the upper carbon, since the detent or escape- 20 ment will alternately engage at its upper and lower end, the teeth upon rod *c*, thus causing the weighted lever to oscillate or rock back and forth and check any tendency of the parts to sudden movement. This construction, accordingly, subserves the purpose of 25 a dash-pot, and opposes the sudden actuation of the movable parts in the well known manner.

The lower carbon *i* of the lamp, is carried within its holder at the end of rod *c*, and within the inclosing globe *k*, while a larger globe *l* may be disposed about the arc and its inclosing globe, if desired.

In the structure of Fig. III., an armature is formed of a plurality of insulated sheet iron segments, well shown in Fig. VII., and carries midway a fine wire coil *m*, which is in shunt relation with the arc, thus adapting the structure for use upon constant 35 current circuits. The form of armature is one capable of being constructed of extremely light weight, which is very desirable in a lamp of this character. The blanks *n*, Fig. V., which are folded to form the armature, are provided with a central opening *n'*, which serves to carry the body of magnetic material away from the field-windings, without reducing its conductive volume at said point. The space thus provided with- 40 in the built-up armature may be availed of for the purpose of mounting the shunt coil *m*, as shown. The segments of this armature are separated by thin insulating strips *n*², and the whole is united or bound to- 45 gether by means of the encircling contact rings *e'*, *e*². Instead of employing a stationary contact rod for conducting current to the upper contact ring *e'* upon the armature, I may employ a spiral of thin flat wire 50 *h''*, which readily adjusts itself to the position of the armature throughout its path of movement, and serves to supply current to the upper contact ring and upper portion of the field coil in circuit therewith.

65 For the purpose of reducing the resist-

ance to the passage of the magnetic lines of force generated by the field-coils, I have also provided a modified type of field structure, best shown in Figs. III. and VI. In this structure, annular iron flanged-rings *p* 70 are provided, which exteriorly serve as electrical conductive segments for making contact with the conducting rings of the armature, and form channels wherein the windings of the field structure are adapted to be 75 positioned. The field-windings are subdivided, being formed of flat insulated wire wound within the said flanged-rings. This field structure, in consequence, affords a better path for the flow of magnetic lines 80 to the exterior casing *a*, since the said sheet iron flanged-rings *p* almost entirely close the circuit within the said casing. The armature, it should be observed, is so constructed and positioned as to afford a gradually receding body of metal midway of its length, which magnetic body abruptly approaches the channel-rings in a position adjacent to the lower contact ring of the armature. The other features of the lamp shown 90 in Fig. III., will be readily understood by making reference to the foregoing description of the first type of lamp.

Having considered the above, one may readily understand the manner in which my improved lamp operates. In the structure described, it is obvious that only the section of the field coil or winding which is spanned by the armature, and embraced between the upper and lower contact rings thereof, will 95 be excited, and, in consequence, the magnetic pull or lifting effect is the same in all positions of the armature and its connected carbon-holder and upper carbon. The lines of force generated by the exciting current 100 will find a path through the external casing *a*, and back through the body of the armature, which is so designed and proportioned as to cause as many as possible of said lines of force to close or find return circuit 105 through the body of the armature below the lower contact ring. This, necessarily, produces a field of force wherein the armature and its connected parts will be supported or floated in the requisite position of adjustment. If the arc is lengthened beyond the 110 normal, however, the flow of current in the windings, which are serially connected therewith, is correspondingly reduced, and the armature descends; while a shortening of 115 the arc increases the flow of current and floats the armature a little higher in the lamp, in order to reestablish the normal arc. Going a little further into the explanation 120 of this action, I may say that the pull or lifting-effect may be said to be approximately equal to the strength of the field multiplied by the current; and, in consequence, the increase or decrease in the flow 125 of such current, results in an increase or 130

decrease in the lifting-effect out of exact proportion thereto, and the adjustment is thereby made very sensitive and efficient.

The function of the fine wire shunt coil *m* is well known; the same merely serving to oppose the magnetic excitation of the field-windings in circuit throughout the operation of the lamp.

In the light of the foregoing description, 10 it will be readily appreciated that my improved lamp is extremely simple in construction and operation, and is positive in its action of maintaining in circuit a field coil of constant exciting effect, and one most advantageously positioned for effecting the adjustment of the upper carbon.

I am aware that the invention herein disclosed is capable of considerable modification, as embodied in working structures, and 20 I claim as my invention, and desire to secure by these Letters Patent, the following:

1. In an adjustment for electric arc lamps, the combination with a serrated rod, of a 25 support for the movable carbon of the lamp and a weighted escapement thereon engaging the serrated rod and adapted to check the sudden movement of the movable carbon support, substantially as set forth.
2. In an electric arc lamp, the combination 30 with a field structure, of a traveling armature therein, a carbon supported there-

by, and a stationary co-acting carbon; said armature comprising sheet iron sections exteriorly expanded and centrally cut away to 35 provide a median recess, and a substantially uniform path for the magnetic lines, the sections being partially folded upon themselves and insulated, and retaining members for securing the sections together, substantially as set forth.

3. In an electric arc lamp, the combination with a field structure comprising annular flanged members of sheet iron, an exterior casing of iron adjacent thereto, sectional field windings disposed between the annular members, a traveling armature interiorly positioned within the field structure, provided with contacts for engaging the annular members; the said armature being 50 formed of sheet iron segments centrally cut away but providing substantially uniform paths for the passage of magnetic lines, an upper carbon supported by the armature, and a stationary co-acting lower carbon, substantially as set forth.

Signed at Cleveland, this 13th day of March, 1905, in the presence of two subscribing witnesses.

JOHN C. LINCOLN.
